UNITED STATES PATENT OFFICE.

FREDERICK STRAIL, OF ROCHESTER, NEW YORK, ASSIGNOR OF THREE-FOURTHS TO ALFRED GREEN, GEORGE W. HOOPER, AND CHARLES L. HOOPER, OF ROCHESTER, NEW YORK.

TROLLEY-WHEEL.

SPECIFICATION forming part of Letters Patent No. 768,959, dated August 30, 1904.

Application filed June 1, 1903. Serial No. 159,678. (No model.)

To all whom it may concern:

Be it known that I, FREDERICK STRAIL, a citizen of the United States, residing at Rochester, in the county of Monroe and State of New York, have invented new and useful Improvements in Trolley-Wheels, of which the following is a specification.

My invention relates to improvements in trolley-wheels.

10 The object of my invention is to provide a trolley-wheel which is adapted to run on the overhead trolley-wire, whether on top or beneath the trolley-wire, also to be used on the underground trolley-wire the same way, or on 15 any copper bar or rod carrying a current to operate a motor, and is more specifically constructed to prevent the same from leaving the wire on curves or passing switches, and this is accomplished by the specifically-constructed 20 trolley without additional means or attachments carried by the harp, which are ordinarily used for preventing the trolley-wheel from jumping off the trolley.

Another object of my invention is to provide a more simple, cheap, and effective trolley-wheel to accomplish the above-referred-to results than has heretofore been produced.

In the accompanying drawings, Figure 1 is a top plan view of my improved trolley-wheel, 30 showing it passing a curve and the trolley-wire shown in dotted lines. Fig. 2 is a vertical sectional view taken on line $\alpha\alpha$ of Fig. 1. Fig. 3 is a vertical sectional view taken on line yy of Fig. 1.

35 Referring now to the drawings, A represents my improved trolley-wheel, the outer portion of which may be of any desired curvature, but is preferably of that shown—that is, with the central or circumferential recess 40 in its sides for the purpose of making the wheel lighter and also for the purpose of saving metal. The wheel is provided with the usual opening C, by means of which it is rotatably mounted upon a spindle D, and thus 45 it is allowed to rotate in the usual manner. The outer periphery of said wheel A is provided with a circumferential groove E, which has at its inner end a concaved trolley-bear-

ing surface e , upon which or against which the trolley is adapted to bear and through which electrical contact with the car is made in the usual manner. In the ordinary trolley-wheel the walls of the circumferential grooves are straight or commonly inclined outward, and thus it will be readily seen that the moment the wheel comes to a curve the wire rides up on the inclined or beveled walls, and thus the trolley-wheel jumps from the trolley, and my invention is particularly designed to obviate this annoyance and delay caused thereby. The trolley-wheel A has the convexed surface G adjacent the inner circumferential bearing-surface e , and the inner side walls of said circumferential groove E are concaved at H, which extends from the convexed portion G to the outer edge of the wheel. The said walls being concaved greater at the portion h , they thus form a more abrupt shoulder at h .

In trolley systems at curves and switches the trolley-wire is slightly curved to form the necessary curve to correspond with that of the rails, and while the trolley-wheel is traveling on the straight portion of the track the trolley rests in the central concaved portion e in engagement with the trolley, and when the wheel engages the curvy portion of the trolley the said trolley will ride up on the convexed surface G and into the concaved portion H, and thus it will be seen that a portion of the curved trolley-wire rests in said groove H, as clearly shown in Fig. 2, and the wire or trolley cannot be forced therefrom on account of the wire being curved, and any upward pressure of the wire or downward movement of the trolley-wheel would bring the trolley in engagement with the abrupt portion h , and thus it will be seen that it will be almost impossible to withdraw the trolley-wheel from the trolley-wire while on curves.

Having thus described my invention, what I claim as new, and desire to secure by Letters Patent, is—

1. A trolley-wheel having a peripheral groove adapted to receive the wire, the inner

faces of the side walls of said groove being concaved.

2. A trolley - wheel having a peripheral groove adapted to receive the wire, and having an inner circumferential bearing-surface for said wire and the inner faces of the side walls of said groove being concaved.

3. A trolley - wheel having a peripheral groove adapted to receive the wire, said groove having a contracted inner wire - bearing surface, and the inner faces of the side walls of said groove being concaved.

4. A trolley - wheel having a peripheral groove adapted to receive the wire, said groove having a contracted inner wire - bearing sur-

face, and the inner faces of the side walls being concaved from said contracted wire-bearing surface to the outer periphery of said wheel.

5. A trolley - wheel having a peripheral groove provided with side walls bent inward at the outer periphery thereof.

In testimony whereof I have hereunto set my hand in the presence of two subscribing witnesses.

FREDERICK STRAIL.
